UNITED STATES PATENT OFFICE

MARTIN T. CHAMBERLAIN, OF JOLIET, ILLINOIS

FIBER-WALL ICE BOX

Application filed September 15, 1927. Serial No. 219,625.

My present invention relates to improvements in refrigerator units of the type, utilizing heat insulated walls that may be formed into refrigerators, ice boxes, etc. The 5 primary object of my invention is the provision of heat insulated walls that are strong and durable and of cellular construction to prevent passage therethrough of heat; which construction is light in weight, but braced to 10 insure the required strength and rigidity. In carrying out my invention I utilize fiber or fibrous material that has been treated with a suitable binder, and this material is compacted to form a cellular, light, but strong 15 structure. The fibrous material with its coating or binder may be either lightly compacted to provide a large proportion of cells in its structure, or it may be closely compacted to reduce the proportion of voids or cells in 20 its structure, and the operation of compacting the material may be accomplished in a mold or press of suitable type. The cellular structure may be made up of wood fiber (excelsior) marsh grass, rice straw, bagasse etc., 25 and the fibrous material may be partially or wholly impregnated or coated with a binder such as oxy-chloride of magnesium, silicate of soda, or, some other inexpensive binding medium that will cement the fibrous material 30 together, or stiffen the fibers in such manner as to hold the fibrous material together as a rigid cellular structure.

The fibrous material with its binder may be closely pressed or compacted to form a 35 strong cellular structure, or the material may be lightly compacted to form a comparatively lighter structure with a greater area of voids. In the latter instance the strength of the structure is reduced and to compensate for 40 this loss in strength I introduce a reinforcing or bracing element within the interior of the wall.

My invention consists in certain novel combinations and arrangements of parts as will 45 hereinafter be more fully set forth and claimed. In the accompanying drawings I have illustrated two examples of the physical embodiment of my invention, wherein the parts are combined and arranged according 50 to modes I have so far devised for the prac-

tical application of the principles of my invention. It will be understood however, that various changes and alterations may be made within the scope of my claims without departing from the principles of my invention. 55

Figure 1 is a view showing in section the lower part of a press or mold in which a rectangular box or container may be fashioned from the coated fiber.

Figure 2 is a perspective view showing a 60 rectangular box, with its hinged door omitted constructed according to my invention and partially broken away to disclose its interior cellular structure.

Figure 3 is a sectional detail view of part 65 of a door to the box of Figure 2 disclosing the cellular interior of the door.

Figure 4 is a sectional view of a box with its back plate in detached position and showing the cellular interior of the box walls. 70

Figure 5 is a sectional detail view at one corner of the ice box or refrigerator unit disclosing a cast wall around the cellular interior and showing also a finishing coat or deposit on the exterior of the cast wall. 75

Figure 6 is an exaggerated or conventionalized view showing some of the fibers with the binder or coating on them for stiffening the fibers and binding them together within the cellular walls. 80

In order that the general arrangement and relation of parts may readily be understood I invite attention to the exaggerated view shown in Figure 6 where the fibers are designated as 1 and may be either round, flat, or of 85 any shape in cross sectional area. The fibers may be laid in any desired relation as parallel, crossed, zig-zagged or in other irregular relations, the essential feature of arrangement being such as will provide for voids or cells between the fibers when the latter are compacted or pressed to form the cellular wall. The fiber of flattened shape is designated as 1 while others may be of various shapes as indicated at 2 where a round fiber 90 is shown.

The binder or stiffening medium 3 is applied to the fibers to partially or wholly impregnate them, and the application of the binder to the fibers is accomplished while the 100

binder is in liquid state, or in plastic state, after which the fibrous material is compacted to form the voids or interstices 4, and the cellular structure is then dried. By the use of baking or heating ovens the binder is dried on the fiber to stiffen it, or the coated, cellular structure may be dried in usual or natural ways, the latter mode of course requiring a longer period of time than the former. In either event the moisture is entirely eliminated from the plastic material and the latter forms a stiffener for the individual fibers and a binder for all of them to hold or retain them in pressed or compacted position and relation.

The cellular structure is indicated as a whole by the numeral 5 in Figures 2, 3, 4 and 5, said structure being fashioned from the impregnated or coated fibers by application of pressure thereto to compact the material and form the interior part of the wall.

In Figure 1 a mold or press is shown in section in which the cellular structure may be fashioned between the inner walls 6 and outer walls 7 of the mold. Between these walls the space 8 is provided for the reception of the fibrous material, and a door frame is indicated at 9. This press is designed to form a box having one open side with the rectangular frame 9 extending around the opening, as a step in the manufacture of an ice box or refrigerating chamber or receptacle.

If the material is to be lightly compacted in the mold to provide a maximum of voids with corresponding decrease in strength, I utilize a reinforcing frame 10 of suitable shape that occupies a central part of the space 8. This reinforcing frame is attached to the door frame 9, and it may be provided with headed spikes or nails 11 projecting therefrom for anchoring means about which the fibers will become interlocked as they are introduced into the space 8 and pressed or compacted therein.

The mixture remains in the mold until the cellular structure has set by drying, from either artificial or natural heat as above indicated, and then the plates or walls of the mold as 7 and if necessary the walls 6 are removed, to permit access to the single piece receptacle or box with its open front. This integral cellular structure is insulated against both heat and moisture as the voids or cells forming dead air spaces are closed against the transmission of heat, and the waterproof coating or binder on the fiber prevents absorption of moisture on the part of the fiber, as well as preventing access of heat to the fibers.

To complete the cellular box-structure a plastic coating 12 is applied to the interior and exterior faces of the walls of the box, and this coating which is also moisture-proof and heat-proof may be sprayed, or "floated" on the surfaces similar to plastering. A finish-

ing coat 13, as of enamel or other suitable material is used to finish the box, and this finishing coat may be applied to the box in any usual or suitable manner, in color or shade of color as desired.

In some instances the cellular structure may be provided with metallic walls as in Figure 4 where the inner wall 14 and outer wall 15 are shown. These metallic walls may have the anchoring means 11 for the fiber, but the reinforcing frame 10 may be omitted as not necessary. The metallic walls may be placed within the press or mold and the fiber introduced therein to form a compact cellular mass within the metal binding walls, and after the structure has been removed from the mold the back plate 16 may be attached to complete the exterior metallic walls of the box. This completed structure of course may be coated, enameled, or painted with suitable finishing material in approved manner.

To complete the ice box or refrigerating receptacle, the door also is made heat proof and moisture proof, using the cellular structure 5 as a base, as indicated in Figure 3 where the door as a whole is indicated as 17 and provided with a jamb 18 cast of suitable plastic material about the cellular structure, and the inner and outer walls of faces 12 of the door may also be cast of plastic material. A hinge block 19 is shown within the cellular structure for the support of the door hinge not shown, and the complementary hinge member 20 is shown on the box in Figure 2.

The thickness of the walls may readily be varied by adjusting the walls of the form or mold in Figure 1, and the density of the fibers in the cellular structure, as before stated, may be varied to decrease or increase the number of cells or the cellular area of the structure.

In some instances the dead air spaces or cells may further be divided by the addition of granular particles of material that is a non-conductor of heat, as kieselguhr, or some other well known material of this nature.

Having thus fully described my invention, what I claim as new and desire to secure by Letters Patent is:—

1. A heat insulating unit comprising inner and outer walls, and an intermediate cellular structure, said structure consisting of fibrous material and a coating on the fibrous material forming a binder for stiffening the material.

2. A heat insulating unit comprising inner and outer walls, anchoring means within the walls, fibrous material coating with said anchoring means and forming a cellular structure between the walls, and a coating on the fibrous material forming a binder for stiffening the material.

3. A heat insulating unit comprising inner and outer walls and a reinforcing element between said walls, lightly compacted fibrous

material between the walls and co-acting with the reinforcing element, and a coating on the fibrous material forming a binder for stiffening the material.

5 4. A heat insulating unit comprising inner and outer walls, a central reinforcing frame rigidly supported between the walls and anchoring means on the frame, lightly compacted fibrous material between the walls and co-acting with the frame and anchoring means, and a coating on the fibrous material forming a binder for stiffening the fibrous material.

In testimony whereof I affix my signature.
